CLAIM

The ornamental design for a vehicle side mirror, as shown and described.

DESCRIPTION

FIG. 1 is an outer perspective view of driver side vehicle side mirror showing our new design;

FIG. 2 is a side view thereof;

FIG. 3 is a rear view thereof;

FIG. 4 is a front view thereof;

FIG. 5 is a top view thereof;

FIG. 6 is a bottom view thereof;

FIG. 7 is an outer perspective view of a passenger side thereof;

FIG. 8 is a side view thereof;

FIG. 9 is a rear view thereof;

FIG. 10 is a front view thereof;

FIG. 11 is a top view thereof; and,

FIG. 12 is a bottom view.

It will be understood that the broken lines shown in the drawings illustrate portions of the vehicle side mirror that form no part of claimed design.
